Primary Examiner — Susan E Krakower*Assistant Examiner* — Lisa A Grabenstetter(74) Attorney, Agent, or Firm — Kenneth H. Ohriner; Perkins Coie LLP(57) CLAIM

The ornamental design for a holder for feminine hygiene articles, as shown and described.

DESCRIPTION

FIG. 1 is a top, front and left side perspective view of a holder for feminine hygiene articles, showing my new design.

FIG. 2 is a front view.

FIG. 3 is a back view.

FIG. 4 is a left side view.

FIG. 5 is a right side view.

FIG. 6 is a top plan view; and,

FIG. 7 is a bottom plan view.

The interior of the holder for feminine hygiene articles, depicted in broken lines, forms no part of the claimed design.

1 Claim, 4 Drawing Sheets(56)
